ATTORNEYS

UNITED STATES PATENT OFFICE.

CHARLES ENGLERT, OF ROCHESTER, NEW YORK.

COPY-HOLDER.

1,289,137.

Specification of Letters Patent. Patented Dec. 31, 1918.

Application filed January 24, 1916. Serial No. 73,924.

To all whom it may concern:

Be it known that I, CHARLES ENGLERT, a citizen of the United States, and resident of Rochester, in the county of Monroe and 5 State of New York, have invented certain new and useful Improvements in Copy-Holders, of which the following is a specification.

The present invention relates to copy holders and more particularly to the type in which a line guide and a work holder are relatively movable for the purpose of pointing out on the work successive lines to be copied, an object of this invention being to provide a 10 construction which will permit the return movement of the movable part relatively to the stationary part by mere pressure on such movable part, so that the manipulation of the shifting or operating devices to effect 15 the release of the movable part, and the provision of devices for cushioning the descent of the movable part will be eliminated. Another object of the invention is to provide a 20 construction which is simple in operation, inexpensive to manufacture and not liable to get out of order. A further object of the 25 invention is to provide means of simple construction for retaining the movable part in the position to which it is adjusted, and at 30 the same time permit the said removable part to be lowered readily without any jarring action. A still further object of the 35 invention is to provide a line guide behind which the work may be quickly fitted, and which is quickly adjustable to conform to work of different widths.

To these and other ends, the invention consists in certain parts and combinations of parts all of which will be hereinafter described, the novel features being pointed out 40 in the appended claims.

In the drawings:—

Figure 1 is a front view of a copy holder embodying the present improvements;

45 Fig. 2 is a vertical section through the copy holder;

Fig. 3 is an enlarged plan view of the copy holder with one end broken away; and

Fig. 4 is an enlarged rear view of the 50 upper end of the copy holder with an end portion broken away.

According to this invention there is provided a supporting-frame embodying preferably a weighted base 1 and a tubular standard 2 rising therefrom and having its 55 lower end fitted in a socket 2^a in the base.

The upper end of this frame 2 may be closed by a cap 3 provided with an eccentric opening, while, within the standard, a partition 4 is arranged also provided with an eccentric 60 opening which is vertically below the eccentric opening in the cap 3, the walls of these two openings serving as guiding means for the work supporting-member.

The work supporting-member preferably 65 embodies a non-circular stem 5 of rectangular cross section operating through the cap 3 and the partition 4, and carrying, at its upper end, a cross-piece 6. This cross-piece is preferably formed from sheet metal, bent 70 substantially into U-shape in cross-section to provide a pair of parallel horizontal flanges 7 which at their centers are provided with perforated lugs 8. Through these lugs a reduced portion 9 on the stem 4 passes, the 75 lugs being held apart by a spacing tube 10 which surrounds the reduced portion 9. A nut 11 on the end of the reduced portion secures the cross-piece 6 to the stem 5.

With the end in view of raising the work 80 support on its supporting-frame, there may be provided a rod 12 guided at 13 on the walls of an opening in the partition 4 and carrying at its upper end a clutch-member 14 which is mounted to swing on said end 85 and is provided with an opening 15 through which the stem 5 passes. When the stem 12 is raised, it lifts the clutch-member 14 which, in turn, by its engagement with the stem 5, raises the work-holder, after which the 90 clutch-member 14 returns to the position shown in Fig. 2. Any suitable means may be employed for raising the rod 12, but preferably a lever 16 is pivoted at 17 to the base 1 and provided at its forward end with a 95 finger piece 18 and, at its rearward end, it extends through a slot in the lower end of the tubing 2, connecting pivotally at 19 with the lower end of the rod 12. A spring 20 is arranged between said lever 16 and the base 100 1 to maintain the lever 16 in an elevated position at its forward end, while an adjustable stop 22 passes through an arm 23 on the lever 16 in order that its lower end may cooperate with the base 1 to adjustably limit 105 the depression movement of the operating lever 16 and thereby control the feeding movement of the work supporting-member.

For retaining the work supporting-member in its adjusted position, two friction 110 grips 24^a are provided for co-operating with opposite faces of the stem 5. These friction

grips are preferably in the form of oppositely extending spring arms formed in one piece with a plate 24 which is secured to the cap 3. These arms yield in an upward direction so that they offer little or no resistance to the upward movement of the work holder, while, upon the downward movement of the work holder, they increase the friction on the stem to such an extent as to support the work holder under ordinary weights yet, at the same time, permitting the descent of the work holder when pressure is applied to the latter in a downward direction. The work is held on the work holder by a work holding means comprising preferably two spring arms 25 extending inwardly from opposite ends of the cross-piece 6 and adjustable toward and from each other. This adjustment may be obtained by providing the spring arms with guide arms 27 forming with the spring arms substantially U-shaped members. These guide arms are mounted to slide on the cross-head 6 and the latter for this purpose has flanges 28 bent from the upper and lower edges thereof at opposite ends to provide sleeves 29 in which the guide arms 27 operate.

For the purpose of holding the turned leaves of stenographers' note books or tablets, the cross-arm or head 6 may also carry two spring arms or clasps 30 extending inwardly from opposite ends of the cross-head, and these arms may also be adjusted toward and from each other, the adjustment being effected by guide arms 31 in one piece with the spring arms to form U-shaped members, the guide arms also being slidable in the sleeves 29 in the direction of the length of the cross-head 6.

It is also desirable to provide in copy holders of this character, a stationary line guide past which the work is carried by the work holder. This line guide, in this instance, comprises a central backing section 32 formed from sheet metal and bent into U-form to provide upper and lower flanges 33, the upper flange having a central lug 34 provided with a slot 35 and secured to the upper face of the cap 3 by screws 36 which also serve for securing the spring plate 24. The backing member also comprises two end sections 37 adjustable on the central section 32 in sleeves formed by bending tongues 38 inwardly from the flanges 33 of the central member. Pivotal connected at 39 to each of the end sections 37 are links 40 which, in turn, are pivoted at 41 to a line guide member. Preferably, this line guide member is flexible and extensible so that it may be made to accommodate work of different widths. As illustrated it is formed of two sections 42 of thin flexible sheet metal, each having a loop 43 at its end surrounding the other section and each being connected with a link 40 by a pivot 41. A plate 44 with its

upper edge 45 deflected rearwardly is secured by tongues 46 to the backing member 32 and thus increases the width of the backing member at the central portion thereof so that the work will have a wide bearing at this point.

The work holder may carry a clamping means for securing it to a desk or typewriter support, and this clamping means is preferably removable and is also adapted to be attached to a number of sides of the base so that any edge of a top of a typewriter support may be clamped. In this instance, the base 1 is provided with a socket 47 at its front and with a transverse socket 48 opening at opposite sides of the support. Any one of these sockets is adapted to receive an arm 49 of a U-shaped clamp while the other arm 50 of said clamp carries an adjusting screw 51 having a hand piece 52 and a clamping portion 53, the clamping portion being opposed to the bottom of the base in order to hold the latter firmly to a suitable support.

The invention will be understood from the foregoing description, but it may be summarized as follows:

The work is secured to the cross head 6 by the oppositely extending clamping arms 25 which are adjusted on the cross head to correspond to the width of the work. The depending portion of the work is introduced between the guide member and the backing member of the line guide by flexing the guide member laterally, the guide member also being adjusted to correspond to the width of the work. The work is raised by depressing the lever 16 periodically and this causes the clutch member 14 to operate upon the stem 5 of the work support. The grips 24 hold the work support in this adjusted position but permit the depression thereof. After one sheet of the work has been copied, it is thrown over the cross head 6 and held by the arms 30, which are also adjusted to correspond to the width of the work.

A work holder constructed in accordance with this invention is inexpensive to manufacture and simple in operation, the operating parts are housed so as to protect it against dust and malicious operation. The size of the supporting frame has been reduced to a minimum and it is thereby adapted to be arranged in a space of small compass. The work holding means which secures the work on the work support is of simple construction and may be easily manipulated. The line guide is of novel form and readily permits the insertion of the work therein while effectively pointing out the line.

What I claim as my invention and desire to secure by Letters Patent is:

1. In a copy holder having a work holder and a line guide, one of which is movable up-

wardly relatively to the other; a mechanism for effecting such relative upward movement having a vertically movable clutch for moving the movable part, means for holding the clutch disengaged from the movable part when the clutch is in its lower or initial position, and means for retaining the movable part in its shifted position, said means having provision which permits such means to release the movable part when pressure is applied to the movable part in a downward direction and the clutch is in its initial position.

2. In a copy holder having a supporting frame provided with a line guide and a work holder provided with a stem guided in the frame; a mechanism for effecting the movement of the work holder on the supporting frame having an operating rod and also having a clutch on the rod to engage the stem of the work holder to shift the latter step-by-step, means for releasing the clutch from the stem when the operating rod is in its lowermost position, and means coöoperating with the stem for retaining the work holder in its shifted position, said means having provision which permits the stem to slide therethrough when pressure is applied to the movable part in a downward direction and the clutch is in its initial position.

3. A copy holder according to claim 2 in which said retaining means is in the form of a friction-device engaging with the stem and yieldable more readily in an upward than in a downward direction.

4. A copyholder comprising a base, a tubular standard rising from the base and closed at its top, a workholder having a stem guided in the top wall of the standard, a partition within the tubular standard, having the stem guided therein, a rod also arranged in the standard and guided in the partition, an operating lever pivoted to the base and having one end extending through the lower portion of the tubular standard and connected to the rod, and a clutch con-

nexion between the rod and the stem arranged entirely within the hollow standard.

5. A copyholder comprising a base, a tubular standard rising from the base and closed at its top, a partition within the standard provided with two openings, a workholder having a stem guided in one of the openings of said partition and in the top of the standard, an operating rod situated within said standard and guided in the other opening of the partition, and a clutch member connected to said rod above the partition and coöperating with the stem and the partition to engage and release the stem.

6. In a copy holder having a supporting frame, and a work support movable on said frame, a line guide carried by the supporting frame and embodying a backing member and a flexible guide member connected together at opposite sides of the copyholder to receive the work between them.

7. A copy holder comprising a work support, a flexible line guide for coöperating with the work support, and links pivotally connected to the flexible line guide and pivotally supported at opposite sides of the copy holder, the pivots of said links being so disposed that the links may swing toward and from each other with the flexing of the line guide.

8. In a copy holder having a supporting frame and a work support movable thereon, a line guide comprising an extensible backing member, and an extensible flexible guide member secured at its ends to the extensible backing member.

9. In a copy holder having a supporting frame and a movable work support, a line guide comprising a central backing section secured to the supporting frame, and backing sections adjustable on said central section, links pivotally connected to said end sections, and an extensible flexible guide member pivotally connected at its ends to said links.

CHARLES ENGLERT.
